H. W. BAHRENBURG & H. MIKKELSEN,
ICE CUTTING MACHINE,
APPLICATION FILED JAN. 9, 1917.

1,283,036.

Patented Oct. 29, 1918.

UNITED STATES PATENT OFFICE.

HENRY W. BAHRENBURG, OF NEWARK, NEW JERSEY, AND HANS MIKKELSEN, OF BROOKLYN, NEW YORK.

ICE-CUTTING MACHINE.

1,283,036.

Specification of Letters Patent. Patented Oct. 29, 1918.

Application filed January 9, 1917. Serial No. 141,366.

To all whom it may concern:

Be it known that we, HENRY W. BAHRENBURG, citizen of the United States, and HANS MIKKELSEN, citizen of the Danish Monarchy, 5 and residents of Newark, county of Essex, State of New Jersey, and Brooklyn, county of Kings, State of New York, respectively, have invented certain new and useful Improvements in Ice-Cutting Machines, of 10 which the following is a specification.

The object of our invention is to provide a generally improved ice cutting machine for cutting ice in the field or in ice houses. One of the objects of the invention is to 15 provide a cutting element in the form of a chain having cutting members of novel and efficient design and construction specially adapted for cutting ice. Another object is to provide a construction in which the cutting element is operated directly by means 20 of an internal explosion motor and to provide suitable supporting means for the latter adapted to maintain at all times the relative position between the cutting element 25 and its operating means. Other objects will appear as this specification proceeds.

Accordingly, our invention is embodied in 30 an ice cutting machine comprising such parts, elements and combinations thereof as is set forth in the following specification while reference is had to the accompanying drawing in which—

Figure 1 is a front elevation of an ice cutting machine embodying our invention with 35 parts in section;

Fig. 2 is a side elevation looking in the direction of arrow 2 in Fig. 1 with parts broken away;

Figs. 3 and 4 are detail views of the cutting element.

The machine is mounted upon runners 5, 5 so as to be easily movable on the ice. The runners may, if desired, be braced or strengthened in any suitable manner not indicated. Secured to each runner is a curved 45 guide member 6 supported by an upright 7. The members 6 and 7 are joined and stiffened by suitable plates or members 8 which form bearings for a shaft 9 operated 50 by a handle 10, shown only in Fig. 1. The opposite end of the shaft carries a ratchet 11. A stop pawl 12 adapted to engage the ratchet 11 is pivotally mounted upon the plate 8. The aforesaid elements may be considered the frame structure of the machine.

The cutting element may be a circular saw or be in the form of a cutting chain 13 which is driven by a sprocket wheel 14 and operated upon a carrier 15 in the form of a plate provided with ribs 16 at both edges. 60 17 designates an idler wheel for the chain journaled in the carrier. The sprocket wheel 14 is fast on a shaft 18 which is driven from the motor shaft 19 by means of bevel gears 20 and 21. 22 represents the 65 motor. 23 is the fuel tank. 24 the fly wheel and 25 the muffler. 26 is the cylinder of the motor. The motor shaft and the gears are inclosed within a suitable casing 27. 28 represents a bearing bracket for the shaft 70 18. The carrier plate 15 is secured to the said bearing bracket at 29. 30 is a guard.

The motor is water cooled from a tank 31 and 32, 32 indicate the pipe connections between the tank, the pump 33 and the cylinder as shown. 34 is a bracket or foot for the motor which is illustrated as being an internal explosion motor of the type known as a detachable boat motor. We have found this type of motor peculiarly well adapted 80 for the purpose, but do not limit ourselves thereto. The motor is mounted upon the platform 36 which also supports the water tank 31, while the bearing bracket 28 is suspended from said platform, the whole making 85 a compact and strong construction.

During the cutting operation the saw 13 sinks into the ice and means must therefore be provided permitting the saw and the operating means therefor to be lowered in 90 order to cut and to be raised when the cut is completed. To this end the platform or frame 36 is supported by a pair of links 37 and 38 on each side of the machine and pivoted at 39, 39 on the runners 5. The 95 links are pivoted to the platform at 40, 40. The platform is connected to the shaft 9 by a flexible cable 41 the one end of which is secured to said platform while the other end passes around a drum 42 fast to the shaft 9. 100

In this manner the saw and its operating means are movably mounted relative to the runners and frame of the machine. That is to say, by disengaging the pawl 12 from the ratchet 11 the shaft 9 may be rotated anti-clockwise to permit a forward and downward movement of the cutter and the motor on the links 37 and 38. To more clearly illustrate this feature, we have indicated in dotted lines a more inclined position of the 110

links with the platform 36 in horizontal position so that the relative positions of the cutter and the motor remain constant. It is therefore at all times within the power 5 of the operator to lower or raise the cutting element by operating the shaft 9. The pawl 12 acts as a safety stop when the cable is wound up on the drum 42. The platform 36 may be moved rearward until the guard 10 30 strikes against the brace 45 which connects the rear links 38 as will be understood. During the cutting operation the saw is lowered in the cut until the lower portion of the bracket 28 strikes the ice.

15 Referring now to Figs. 3 and 4, it will be seen that the cutting chain 13 comprises the inside links 50 and the outside link 51 which are joined in the usual manner to form a chain. Each inside link is provided with a 20 saw tooth 52 which is wedge shaped or provided with inclined sides 53 to form a cutter in which the cutting portion 54 is of greater width than the base or link portion 50. The outside links are provided with teeth 55 25 having a cutting portion 56 of greater width than the base or link portion 51. The inner sides of the teeth 55 are parallel while the outer sides 57 are inclined toward each other. In this manner a straight groove 30 is provided which runs upon the ribs 16 of the carrier 15. We have found that because the cutting portions of the teeth are wider than the base or link portions, the chain cuts with ease through the hardest ice without 35 jamming or stopping.

The construction and operation of the machines will be understood from the foregoing description. It will be seen that the saw or cutting chain may be lowered so as 40 to cut into corners and quickly withdrawn in case obstructions are met with. The chain is kept free from ice shavings because the links move in a wide path provided by the

widened cutting portions. The machine is very light yet strong in construction. The 45 guides 6 cause the links to move in vertical planes and prevents undue side strains.

While we have illustrated and described the preferred form of our invention it is obvious that changes in the detailed construction may be made without departing from the scope of the appended claims.

We claim.

1. A machine for cutting ice, comprising a pair of runners, a cutting member, actuating means for said cutting member, means for jointly supporting said cutting member and said actuating means, said means including parallel links and means for pivoting said parallel links at one end respectively to said pair of runners. 55

2. A machine for cutting ice, comprising a pair of runners, a cutting member, actuating means for said cutting member, driving means of fixed effective length connecting said actuating means with said cutting member, means for jointly supporting said cutting member and said actuating means, said means including parallel links and means for pivoting said parallel links at one 65 end respectively to said pair of runners. 70

3. A machine for cutting ice, comprising a pair of runners, a cutting member, a self-contained power plant, driving means of fixed effective length connecting said power 75 plant with said cutting member, means for jointly supporting said cutting member and said power plant, said means including links and means for pivoting said parallel links at one end respectively to said pair of 80 runners.

In testimony whereof we have signed this specification.

HENRY W. BAHRENBURG.
HANS MIKKELSEN.
